[57] **CLAIM**

The ornamental design for a condiment mill, as shown and described.

DESCRIPTION

FIG. 1 is a top plan view of a condiment mill showing my new design;

FIG. 2 is a right side elevational view thereof;

FIG. 3 is a front elevational view thereof;

FIG. 4 is a rear elevational view thereof;

FIG. 5 is a bottom plan view thereof; and

FIG. 6 is a perspective view thereof.

The side opposite to that shown in FIG. 2 is the mirror image thereof.
